Primary Examiner — Darlington Ly*Assistant Examiner* — Daniel J Domino(74) *Attorney, Agent, or Firm* — Wilson, Sonsini, Goodrich & Rosati(57) **CLAIM**

The ornamental design for a display panel with graphical user interface, as shown and described.

DESCRIPTION

The FIGURE is a front view of a display panel with graphical user interface, showing our new design.

The broken lines showing a display panel and elements of the graphical user interface illustrate portions of the article, and form no part of the claimed design.

1 Claim, 1 Drawing Sheet(56)
